UNITED STATES PATENT OFFICE.

ANTHONY J. OLIVA, OF ASTORIA, NEW YORK.

MULTICOLOR-PRINTING MACHINE.

1,101,951.

Specification of Letters Patent. Patented June 30, 1914.

Application filed April 19, 1912. Serial No. 691,914.

To all whom it may concern:

Be it known that I, ANTHONY J. OLIVA, a citizen of the United States, and residing at Astoria, Long Island, in the county of Kings 5 and State of New York, have invented certain new and useful Improvements in Multi-color-Printing Machines, of which the following is a specification, such as will enable those skilled in the art to which it appertains to make and use the same.

This invention relates to machines for printing various designs on fabric or paper of any kind or class in a plurality of colors, and the object thereof is to provide an improved machine of this class which employs stereotype plates or rollers and lithographic ink; a further object being to provide a machine of the class specified by means of which lithographic ink in its normal condition may be used and designs produced in fast colors without subjecting the printed designs to further treatment other than drying; and with these and other objects in view the invention consists of a machine of the 25 class specified constructed and operating as hereinafter described and claimed.

The invention is fully disclosed in the following specification of which the accompanying drawing forms a part, in which the 30 separate parts of my improvement are designated by suitable reference characters in each of the views, and in which:

Figure 1 is a side view of my improved multi-color printing machine, or the operative parts thereof, the steam drying drums, the steam drying pipes, the supply roller and the rewinding roller being not shown in this view: Fig. 2 a view of the opposite side of the machine, as shown in Fig. 1 with 35 parts omitted and only the bottom part of the machine being shown: Fig. 3 a vertical section on the line 3—3 of Fig. 1: Fig. 4 a section on the line 4—4 of Fig. 1 and on enlarged scale: Fig. 5 a section on the line 40 5—5 of Fig. 4: Fig. 6 a view of certain details of the construction looking in the direction of the arrow 6 of Fig. 4: Fig. 7 a diagrammatic side view of the machine and showing the movement of the sheet to be 45 printed: Fig. 8 a section on the line 8—8 of Fig. 9: Fig. 9 a side view of a detail of the construction; and Fig. 10 a partial section on the line 10—10 of Fig. 5.

In the practice of my invention I provide 50 a main upright frame 1 comprising two side

members 2 which are connected by transverse bolts 3 which may be arranged in any desired manner, but one of which is arranged near the bottom, in the construction shown, and the other two near the top, but it will be understood that any desired number of these bolts may be employed. In the central bottom portion of the sides of the frame are vertically movable bearing blocks 4 in which is mounted a platen drum 5 which is made 55 vertically adjustable by means of screws 6 provided at their upper ends with beveled gears 7, and a transversely arranged shaft 8 having corresponding gears 9 provided at one end with a crank wheel or similar device 10. In the top of the main frame is mounted a roller 11 having a shaft 12 mounted in vertically adjustable bearings 13, and said bearings are made adjustable by means of vertically arranged screws 14 provided 60 with crank wheels or similar devices 15.

Mounted on the platen drum 5 and roller 11 is an endless platen belt 16 composed of rubber, rubber and canvas or any other suitable elastic material, and supported in any 65 desired manner at one side of and at a suitable distance from the drum 5 and roller 11 and parallel therewith are two steam drying drums 17 and 18 arranged one above the other, and below which is a rewinding roller 70 19 between which and the drum 5 is a supply roller 20 on which is wound the sheet of material to be printed. Above the supply roller 20 are two drag rollers or rods 21 and 22 arranged one above the other, and approximately 75 in the same horizontal plane with the upper drag roller or rod 21, and midway between the drum 5 and roller 11 is a guide roller 23, and between the roller 11 and the upper steam drum 17 is placed, in a horizontal plane, a plurality of steam pipes 24. This construction and arrangement being clearly shown in Figs. 1 and 7.

The sheet 25, on which the desired design is to be printed, is wound on the roller 20 and is passed around the drum 5 and roller 11 in the direction of the arrows α , and from the roller 11 said sheet passes over the steam pipes 24, around the upper steam drum 17, then between the drums 17 and 18 and around the drum 18 and then connected with the rewinding roller 19. Arranged at the opposite sides of, and beneath the drum 5, are a plurality of ink preparing and applying devices or mechanisms 26 three of which 80

26

are employed on each side, as here shown but it will be understood that the number of these ink preparing and applying devices will be controlled by the number of colors which it is desired to employ in printing any particular design or designs. The ink preparing and applying devices 26 are all exactly of the same form, construction, and operation and a description of one will therefore apply to all. Each of these devices employs in its construction a rigid rectangular frame 27 comprising parallel side bars 28 and an outer transverse end bar 29, and the side bars 28 are provided with outwardly directed angle members 30 which are adjustably secured to angle brackets 31, which in turn are secured to the side members 2 of the main frame by screws or bolts 32, or in any desired manner, and the angle brackets 31 are provided with slots 33 through which are passed bolts 34, and by means of this construction the frame 27 is made adjustable toward and from the platen drum 5. The side bars 28 of the frame 27 are provided adjacent to the drum 5 with recesses 35, and midway thereof with other recesses 36, and in the outer end of said frame is an ink font or holder 37 which is box-shaped in form, and ranges transversely of the frame, and mounted in the front thereof, which is open, is a transverse metal roller 38. Mounted in the recesses 35 in the side bars 28 of the frame 27, and adjacent to the platen drum 5, is a transverse stereotype mandrel 39 on which is placed a stereotype plate 40 which is cylindrical in form and on which is placed part of the design to be printed, and it will be understood that the design on the stereotype plate 40 of the stereotype mandrel 39 in the different ink applying devices or mechanisms 26 is different in form, but all of which taken together make up the complete design to be printed. The shaft 41 of the mandrel 39, or the opposite ends thereof, are provided with bearings 42 which are made adjustable longitudinally of said shaft and radially or toward and from the drum 5, and it will be understood that the longitudinal adjustment 50 also adjusts the mandrel 39 transversely of the face of the drum.

The adjustment toward and from the drum 5 is effected by screws 43 which press on the bearings 42 and this adjustment or movement is for the purpose of increasing or decreasing the pressure of the mandrel on said drum. The longitudinal adjustment of the mandrel or of the bearings 42 by which the longitudinal adjustment of the mandrel 60 is produced, is effected by means of screws 44. In order to accomplish this result the bearings 42 are provided with inner movable members 45 and the screws 44 are passed inwardly parallel with the shaft 41 and operate on the members 45 and by manipulating

the said screws at the opposite ends of the shaft 41 said shaft and the mandrel may be adjusted transversely of the face of the drum, as will be readily understood.

Mounted between the roller 38 and the mandrel 39 and in the same plane thereof and beginning with the roller 38 are rollers 46-47-48 and 49 all of which are composed of rubber or have a rubber facing, and the rollers 38-47-48 and 49 have a rotary movement only, and the roller 49 operates in connection with the stereotype plate 40. Mounted over and operating in connection with the roller 49 is a roller 50 composed of rubber or having a rubber face, and rearwardly thereof and slightly below the roller 50 is another roller 51 preferably of metal. The roller 50 has a rotary movement only, while the roller 51 has both a rotary and longitudinal movement.

Mounted at one side of the frame 27 in a bracket 52 is a longitudinally movable bar 53 composed of separate parts adjustably connected at 54, and the front end of which is forked and provided with a roller wheel 55 which operates in connection with a cam disk 56 fixed to the shaft 41, and the rear end of the bar 53 is connected with the corresponding end of the shaft of the roller 46, and mounted on the opposite ends of the shaft of the roller 46 are rock arms 57 pivoted to the side bars 28 of the frame 27 at 58, and which extend below the frame 27 and are connected by a cross bar 59, and mounted in the upper ends of the arms 57 is a roller 60 which is made to contact with the roller 46, but which operates in connection with the rollers 38 and 47 intermittently, and connected with the side bars 28 of the frame 27 are springs 61 which operate to hold the roller wheel 55 in connection with the cam disk 56, and to force the roller 46 into contact with the roller 47, which operation forces the roller 60 into the dotted position shown in Fig. 5, and out of contact with the roller 38, and the operation of the cam disk 56 throws the roller 46 into contact with the roller 38 intermittently, as above stated.

The end portion of the shaft 41 of the mandrel 39 opposite the cam disk 56 is provided with a gear 62 which meshes with a smaller gear 63 on the corresponding end of the shaft of the roller 49, and the opposite end of the shaft 41 is provided with a crank disk 64 provided in its outer face with a diametric groove 65 in which is mounted a block 66 made adjustable by means of a set screw 67, and pivoted to the block 66 is an arm 68 which is connected with an arm 69 loosely mounted on the shaft 70 of the roller 38, and the arm 69 is provided with a spring pressed pawl 71 which operates in connection with a ratchet 72 fixed to the shaft 70, and this construction imparts to the roller 38

an upward and forward step by step movement through the ink 73 in the font or box 37.

Each of the shafts 41 of each of the mandrels 39 of each of the ink applying devices 26, opposite the cam disks 56 is provided with a gear 74, and these gears mesh with a large gear 75, mounted on a stud shaft 76 in line with a shaft 77 of the platen drum 5, and the gears 74 are adjustable on the mandrel shafts 41, as clearly shown in Figs. 8 and 9, said gears being rotatably mounted on sleeves 78 adjustable longitudinally on said shafts, and the gears 74 are held on the sleeves 78 by collars 79 having set screws 80.

The gears 74 are provided on their outer sides with ears 81 in which are mounted worms 82 which mesh with corresponding worm gears 83 on the sleeves 78 and the opposite end portions of the worms 82 are provided with cylindrical heads 84 having radial holes 85 to receive the ends of crank pins or similar devices for turning said worms, which operation is performed by hand, and the object of this construction is to provide for the adjustment of the mandrel 39 circumferentially so that the design or designs on the stereotype plates 40 may be put in perfect registration with each other.

Mounted beneath and transversely of the drum 5 is a power shaft 86 one end of which is provided with a pinion 87 which meshes with the gear 75, and the opposite end of which is provided with a belt wheel 88 and said shaft is also provided inwardly of the belt wheel 88 with a box cam 89 having a spiral groove 90.

Mounted horizontally and at the outer side of the main frame adjacent to and over the box cam 89 and in brackets 91 secured to said frame is a rock shaft 92, and said shaft is provided between the brackets 91 with a downwardly directed arm 93^a the lower end of which is provided with a pin 94 which operates in the groove 90 of the box cam 89 and by means of this construction the shaft 92 is given a rocking rotary movement.

The shafts 93 of the rollers 51 of each of the ink applying devices or mechanisms 26 are projected on the side of the machine on which the shaft 92 is mounted, and these shafts are provided with grooved wheels 94 and the shaft 92 is provided with arms 95 which correspond in number with the number of ink applying devices 26, and which are provided with forks 96 having inwardly directed pins 97 which operate in the grooves 98 of the wheels 94, and the object of this construction is to give the rollers 51 a reciprocatory longitudinal movement.

As hereinbefore stated the object of this machine, or one of its objects, is to print a design on fabric, paper, or the like and especially silk, in different colors and at one

operation, and to print said design in fast colors by using lithographic ink, this result has never heretofore been produced, except by using stone or other tablets and by processes which made a number of operations necessary, or one for each color, but with my improvement, the desired object can be obtained at one operation, and the number of colors depending on the number of ink preparing and applying devices. 75

In the old method of printing different colors by the use of tablets or prints the perfect registration of the different colors in the print produced was very difficult if not impossible by reason of the fact that the article to be printed had to be taken from one machine to another, but with my improvement the various adjustments provided for, or the adjustments of the printing mandrels of the different ink applying devices, 80 provide means whereby the registration of the different stereotypes printing different colors can be exactly effected and the desired work accomplished in the best possible order, and in the shortest possible time, and at one 90 operation of the machine.

It is a well known fact that lithographic ink is not a liquid or flowing body but is more of a plastic or viscid character, and this ink must in the operation of the machine be broken up and entirely distributed so that it will completely cover the rollers 49 by which the colors are applied to the stereotype plates, and this result is accomplished by the movement of the various rollers between the rollers 38 and the rollers 49 of the ink applying devices or mechanisms. 95

It will be understood that the rollers 49 are given a continuous movement by the gears 62 and 63, and the rollers 38 are given an intermittent or step by step movement by the parts 68—69—71 and 72, while the rollers 46 and 60 are given a forward and backward movement by the parts 53—55—56—57 and 59, all of the colors employed 100 being also capable of rotary movement in the usual manner. In this operation the rollers 38 turn in the direction of the arrow a^2 and pick up particles of the ink in the font or box 37, and the rollers 46 and 60 115 receive the ink from the rollers 38 and apply it to the rollers 47 and in this operation the particles of ink are broken up and spread over the rollers 46—47 and 60. The rollers 51 in addition to having a rotary 120 movement also have a longitudinal movement, and this operation takes the ink from the rollers 47 and applies it to the rollers 48 and the ink is more finely and evenly applied to said last named rollers, and the rollers 49 take the ink from the rollers 48 and apply it to the stereotype rollers or mandrels 39, and in this operation the ink is completely and evenly applied to the rollers 49 by the rollers 48 and 50 and the 130

rollers 49 are given a continuous, even and smooth coating of said ink so as to perfect the transfer of the ink by the rollers 49 to the stereotype rollers or mandrels 39, or 5 stereotype plates mounted thereon.

It will be observed that all of the printing or stereotype rollers 39 are mounted in an arc of a circle below and at the sides of the platen drum 5, and by reason of the 10 fact that said drum is vertically movable or adjustable it may be raised, when desired, above the said printing or stereotype rollers in order to permit of, and facilitate, the operation of adjusting said rollers into the 15 desired position and the adjusting of the stereotype plates thereon, and this is one of the chief features of applicant's invention, another feature thereof being the possibility of adjusting the stereotype rollers longitudinally and rotarily in order to cause the stereotype printing plates thereon to properly register, in the operation of printing a design of different colors at one operation on a strip of cloth or other material, 20 and means for effecting the longitudinal adjustment of said stereotype rollers, is clearly shown in Fig. 4, and means effecting the rotary adjustment of said rollers is clearly shown in Figs. 8 and 9, and these 25 rollers are also, as hereinbefore stated, adjustable toward and from the platen drum 5.

Another feature of my invention, and wherein it differs from others of its class is in the fact that the platen drum 5 is turned 30 by friction of the stereotype rollers 39 and not by direct gearing, as in other machines of this class, and this also facilitates the assembling of the various parts of the machine or press, and the adjustment of said 35 rollers, as hereinbefore described, and by means of this construction the stereotype rollers may be independently turned or rotated and adjusted into the desired position, when said platen drum is raised out of contact therewith.

My invention is not limited to the exact details of construction herein shown and described, and various changes therein and modifications thereof, may be made, within 40 the scope of the appended claim without departing from the spirit of my invention or sacrificing its advantages.

It will be understood that the steam dry-

ing drums 17 and 18 may be of the usual 55 form and construction, and these drums together with the rollers 19 and 20, the steam pipes 24 and the rods or rollers 21 and 22 may be supported in any desired manner, and in connection with the main frame of the machine, or in any other way, and, as 60 will be understood, the steam drying drums 17 and 18 and the steam pipes 24 are for the purpose of thoroughly drying the printed sheet 25 or the designs printed thereon before said sheet is rewound on the roller 19. 65

Having fully described my invention what I claim as new and desire to secure by Letters Patent is:—

In a machine of the class described, a platen drum, and a plurality of frames 70 mounted at the sides of and beneath said drum and each of which is provided with a stereotype roller operating in connection therewith, ink holders mounted in said frames, ink rollers mounted adjacent to and 75 operating in connection with said ink holders and having a step by step movement, other rollers mounted adjacent to and operating in connection with the stereotype rollers and geared in connection therewith, 80 two independent rollers mounted between the ink rollers and the rollers geared in connection with the stereotype rollers, and one of which is in connection with the last named rollers, rollers mounted above and 85 in contact with the two independent rollers and longitudinally movable, other rollers mounted over the rollers geared in connection with the stereotype rollers and in contact therewith, rollers mounted between the 90 ink rollers and the adjacent independent rollers and movable toward and from each, and adapted to contact with each alternately, and other rollers mounted over the inking rollers and adapted to bear thereon intermittently and always in contact with the last 95 named rollers.

In testimony that I claim the foregoing as my invention I have signed my name in presence of the subscribing witnesses this 100 18th day of April 1912.

ANTHONY J. OLIVA.
